UNITED STATES PATENT OFFICE.

MAURICE E. REAGAN, OF PITTSBURGH, PENNSYLVANIA, ASSIGNOR TO WESTINGHOUSE ELECTRIC & MANUFACTURING COMPANY, A CORPORATION OF PENNSYLVANIA.

AUTOMATIC RECLOSED CIRCUIT INTERRUPTER.

Application filed April 18, 1922. Serial No. 555,184.

To all whom it may concern:

Be it known that I, MAURICE E. REAGAN, a citizen of the United States, and a resident of Pittsburgh, in the county of Allegheny and State of Pennsylvania, have invented a new and useful Improvement in Automatic Reclosing Circuit Interrupters, of which the following is a specification.

My invention relates to automatically closing circuit interrupters and particularly to interrupters of the type known as sectionalizing switches.

One object of my invention is to provide a sectionalizing switch that shall be opened automatically when the current that is transferred between the sections exceeds a predetermined value by reason of an overload or short-circuit condition upon one of the sections, and that shall be reclosed when such abnormal condition is eliminated.

Another object of my invention is to provide a control system for a switch of the above-indicated character that shall render the sectionalizing switch operative to connect the two sections when the sum of the voltages, and, consequently, the average of the voltages of the two sections, attains or exceeds a predetermined value.

Another object of my invention is to provide a system, of the above-indicated character, comprising means that shall preclude the operation of the control system until a predetermined interval after the opening of the sectionalizing switch.

A further object of my invention is to provide a control system, of the above-indicated character, that shall effect the reclosing of the sectionalizing switch when both voltage and load conditions upon both sections are normal and that shall derive its operating voltage from either section, thus being operative irrespective of whether or not the two sections are independently energized.

In practicing my invention, I employ the principle set forth in Patent No. 1,363,666, issued December 28, 1920 to Joseph N. Mahoney and Walter M. Austin and assigned to the Westinghouse Electric and Manufacturing Company. In that patent is disclosed the novel means of arranging an operating coil of a sectionalizing switch which consists in connecting the operating coil be-

tween the mid point of a resistor that is connected between the two sections that are to be controlled and the return conductor of the system. The closing coil is thus energized in accordance with the average value of the potentials of both sections and the switch may be closed only when that average value attains or exceeds a predetermined value.

In the system herein set forth, I employ the arrangement disclosed by Mahoney and Austin in the above-mentioned patent and provide other controlling devices that have been found desirable. I provide, for example, an overload relay that controls the circuit of the operating coil of the sectionalizing switch and is latched in its open position, when actuated, to maintain the operating coil de-energized.

Upon the opening of the sectionalizing switch a time-element device is actuated to render the control apparatus operative for effecting the reclosing of the sectionalizing switch. A relay that is responsive to the average value of the potential differences of the two circuits is rendered effective to release the overload device when the average value of the potential differences of the two circuits attains a predetermined value, whereupon the operating coil of the sectionalizing switch is energized to effect the reclosing of that switch.

The single figure of the accompanying drawing is a diagrammatic view of a control system for an automatic sectionalizing switch embodying my invention.

Two circuit section conductors 1 and 2 have a common return conductor 3 and are adapted to be connected normally by a circuit-controlling device or sectionalizing switch 4 while conditions in the circuits of both section conductors 1 and 2 are normal. When overload or short-circuit conditions occur in either section, as, for example, in section 2, the value of the current transferred between sections 1 and 2 attains or exceeds a predetermined value at which an overload relay 5 is adjusted to operate. The sectionalizing switch 4 is thereupon permitted to open to disconnect the section conductors 1 and 2.

The interrupter comprises the main switch 4, an operating coil 6 and two auxiliary

switches 7 and 8 that are open when the switch 4 is closed and that are closed when the switch is open.

The overload relay 5 comprises a switch 9 that controls the circuit of the operating coil 6 of the sectionalizing switch 4, a main operating coil 10 that controls the operation of the switch 9 through a pivoted member 11 and a latching member 12 that engages the pivoted member 11 to latch the same in such position that the switch 9 is maintained open.

A reset coil 13 is provided to actuate the latch member 12 against the force of a spring 14 to such position that the pivoted member is released. The pivoted member is thereupon actuated by a spring 26 to effect the closure of a switch 9.

When the sectionalizing switch 4 is actuated to disconnect the two sections 1 and 2, two resistors 15 and 16, that are connected between the sections 1 and 2, are rendered effective to provide means whereby the average value of the potential difference of the two circuits may be obtained.

After the opening of the switch 4, the switch 8 is closed to connect the operating coil 17 of a time element relay 18 between the mid point of resistors 15 and 16 and the return conductor 3. After a predetermined interval determined by the setting of the dash-pot 19 of the time-element relay 18, a switch 20 is closed to complete the circuit of the operating coil 21 of a potential relay 22. The coil 21 is connected in series with a resistor 23 between the mid point of the resistors 15 and 16 and the return conductor 3 through the switch 20.

When the average value of the potential differences across the sections 1 and 2 attains a predetermined value corresponding to the setting of an adjustable means 24 of the potential relay 22, a switch 25 is closed. The switch 25 controls the energization of the reset coil 13 of the overload relay 5.

Assuming the occurrence of a short circuit or overload on the section 2, the excess current caused to traverse the switch 4 and the circuit conductor 1 would effect the actuation of the overload relay 5 to open the switch 9. The sectionalizing switch 4 would thereupon open, and, after a predetermined interval controlled by the setting of the dash-pot 19, the switch 20 would close.

The closing of the switch 25, however, would be effected only when predetermined load conditions obtained on the circuit 2 and the conditions on the circuit 1 were normal.

During tests that were conducted to determine the sensitiveness of the arrangement, resistors having a resistance of 0.575 ohms were connected between the section conductor 2 and the conductor 3, the normal voltage of the circuit being 250 volts. The

overload relay 5 was adjusted to operate at a value of current corresponding to this condition, to open the sectionalizing switch 4. The resistors 15 and 16 each having a resistance of 5 ohms, the total resistance between the section conductor 1 and the conductor 3, including the load resistance on the section 2, was 10.575 ohms.

At a voltage of 250 volts on the section 1, the current through the resistors 15 and 16 and the load resistance on the section 2 would be 23.62 amperes. Under these conditions, the potential difference between the mid point of the resistors 15 and 16 and the conductor 3 that would be effective in energizing the coil 21 of the voltage relay 22 is 131.9 volts.

Upon changing the value of the resistance connected to the circuit 2 to substantially 0.8 ohm, the resistance from the conductor 1 to the conductor 3 amounted to 10.8 ohms. The current traversing the circuit including that value of resistance at the voltage of 250 volts was 23.15 amperes. The potential difference that was effective under this condition of resistance for energizing the coil 21 of the voltage-responsive relay 22 was, therefore, 134.25 volts. The relay 22 operated at this value to close the switch 25 to energize the reset coil 13 of the overload relay 5. The switch 9 was thereupon closed and the operating coil 6 was energized to effect the reclosing of the sectionalizing switch 4.

The potential relay 22, being sensitive to a difference of approximately $2\frac{1}{2}$ volts at a predetermined value of voltage across the coil 21 and its resistor 23, very sensitive control of the sectionalizing switch 4 may be obtained in accordance with predetermined values of resistance under overload or short-circuit conditions in either circuit. The sectionalizing switch 4 may, therefore, be opened when the resistance across either section 1 or 2 is lowered to or below the value of 0.575 ohm and may be reclosed when the value of the resistance attains or exceeds 0.8 ohm.

By means of the arrangement herein disclosed, relatively great sensitivity in the operation of the sectionalizing switch is obtained by means of standard relays that are ruggedly constructed for satisfactory operation under extreme service conditions.

My invention is not limited to the specific devices that are illustrated or to the specific arrangement that is shown, since modifications may be made therein within the spirit and scope of my invention, as set forth in the appended claims.

I claim as my invention:

1. In an electrical distribution system having a common return conductor, the combination with a circuit-controlling device provided with an operating coil for connect-

ing the two circuit section conductors of the system, of two resistors connected between the circuit sections, means for normally connecting the operating coil between the mid-point of the resistors and the common return conductor comprising a resistor and a switch controlled by an overload device, means for latching the switch in open position after its operation, a voltage relay for effecting the release of said switch when the average potential of the two circuit sections attains a predetermined value, and a time-element relay for controlling the energization of the voltage relay.

15 2. In a system of distribution, the combination with two circuit section conductors, a common return conductor and a connecting device provided with an operating coil for connecting the two section conductors, of an overload switch for opening the circuit of the coil when excessive current traverses the connecting device to permit the connecting device to open, resistance means for limiting the exchange of current when the connecting device is open, a control relay, an electrical timing relay, an interlock switch controlled by the connecting device to control the energization of the timing relay, means controlled by the timing relay after a predetermined interval for energizing the control relay, and means controlled by said control relay when the voltages of both circuit sections bear a predetermined relation for reclosing the overload switch to control the energization of the operating coil of the connecting means.

20

25

30

with a predetermined relation between the voltages of both circuit sections for reclosing the overload switch to reenergize the operating coil of the connecting means.

3. In a system of distribution, the combination with two circuit section conductors, a common return conductor and a connecting device provided with an operating coil for connecting the two section conductors, of an over-load switch for opening the circuit of the coil when excessive current traverses the connecting device to permit the connecting device to open, resistance means for limiting the exchange of current when the connecting device is open, a control relay, an electrical timing relay, an interlock switch controlled by the connecting device to control the energization of the timing relay, means controlled by the timing relay after a predetermined interval for energizing the control relay, and means controlled by said control relay when the voltages of both circuit sections bear a predetermined relation for reclosing the overload switch to control the energization of the operating coil of the connecting means.

In testimony whereof, I have hereunto subscribed my name this 14th day of April 1922.

MAURICE E. REAGAN.
